UNITED STATES PATENT OFFICE.

JOHN F. KERR, OF NEW YORK, N. Y.

SECTIONAL METALLIC CABINET.

No. 907,507.

Specification of Letters Patent.

Patented Dec. 22, 1908.

Application filed April 28, 1908. Serial No. 429,672.

To all whom it may concern:

Be it known that I, JOHN F. KERR, a citizen of the United States, residing at New York, in the county of New York and State 5 of New York, have invented a new and useful Improvement in Sectional Metallic Cabinets, of which the following is a specification.

My invention relates to sectional metallic cabinets; and the object thereof is to provide 10 a sectional cabinet composed of a plurality of units, and a further object is to provide improved means for coupling and locking together said units to effect a composite whole structure, and to prevent the accidental dis- 15 placement, disarrangement or disconnection of the units either vertically, laterally or transversely, and for other purposes herein-after more fully described and particularly pointed out in the claims.

20 In the accompanying drawings illustrating my invention, Figure 1 is a perspective view of a cabinet comprising a plurality of sectional units coupled together; Fig. 2 is a perspective view of one of the sectional units; 25 Fig. 3 is a sectional view of a cabinet of my invention taken on the line 1—1 of Fig. 1, and Fig. 4 is a transverse sectional view of the same on the lines 2—2 of Fig. 1.

My invention includes, generally, a plurality of rectangular cases of corresponding 30 shape and dimensions, adapted to be coupled and locked together vertically and laterally, each of which is provided with a hook and an eye on its rear lower and upper edges, respectively, the hooks and eyes on adjacent 35 cases or units being adapted to interlock. Each unit is also provided with a tongue on one side and a keeper on its opposite side, they being adapted to couple the units together laterally. Projecting strips on the 40 sides of each section or unit, adjacent to its front face, are adapted to embrace the lower edges of the section above and secure the two sections in perfect vertical alinement.

45 Referring now to the drawing, 1 designates my sectional cabinet, composed of a plurality of rectangular units 2 made of any suitable sheet metal. Each unit, as shown, is provided with a door 3 hinged at the bottom and secured at the top by a suitable latch 4. The units 2 are adapted to be assembled and built together either vertically or horizontally or both, and for this purpose I provide means for coupling the adjacent 55 edges of the units when arranged vertically, and also means for uniting the abutting

sides thereof when arranged in horizontal relation, both of said means coöperating to form a composite whole structure when same is built both vertically and horizontally and 60 retain the units in perfect alinement and correspondence, and to prevent accidental displacement, and at the same time permit the convenient disconnection of the units or the addition thereto. For the said purposes, I 65 provide each unit 2 with a hook 5 on the lower edge of the back face, and on the upper edge of the back is provided a tab 6 projecting slightly above the top of the unit and bent outwardly at an acute angle to the 70 plane of the back of the unit to accommodate the hook 5. Said tab is pierced to form an eye 7 to receive the hook 5. Each of the units is also provided with reinforcing vertical metal strips 8 on its sides adjacent to its 75 front edge, which projects slightly above the top of the unit thus forming flanges 9 which are adapted to embrace the sides of the unit next above and secure same in vertical alinement therewith. On one side of each unit 2, a 80 metal strip 10 is suitably secured horizontally at its ends, intermediate of which the strip is bent slightly outwardly thus forming with the side a keeper 11. On the opposite side of each unit and at corresponding position with the strip 10, a downwardly extending metal tongue 12 is secured, which is adapted to fit into the keeper 11 on the side of an adjacent unit. In uniting the units 85 vertically, the hook 5 is coupled with the tab 90 6 through the eye 7, therein, at the backs thereof, and the upper unit fits between and is embraced by the flanges 9 on the top of the lower unit. In arranging the units horizontally to build the cabinet laterally, the 95 tongue 12 on one unit engages the keeper 11 on an abutting unit, thereby securing the units and vertical tiers against lateral displacement.

To separate the units, the top one may be 100 raised at the front to disengage the tongue 12 and the hook 5 from their respective co-acting parts, or an entire vertical tier of units may be lifted out of engagement with those adjacent thereto.

Having thus described my invention, what I claim as new and desire to be secured by Letters Patent, is—

1. A sectional cabinet comprising a plurality of units, hooks on the lower edges of 110 the backs thereof, perforated tabs on the upper edges thereof adapted to couple with

said hooks, and vertical flanges on the sides thereof adjacent to the front adapted to embrace the sides of the unit above and preserve their vertical alinement, substantially as described.

2. A sectional cabinet comprising a plurality of units, hooks on the lower edge of the backs thereof, perforated tabs on the upper edges thereof adapted to couple with said 10 hooks, vertical flanges on the sides of each unit adapted to embrace the sides of the units above, a tongue on one side of each

unit and a horizontal strip on the opposite side thereof adapted to engage the said tongue on the abutting unit, as and for the 15 purposes described.

In testimony whereof, I have hereunto signed my name in the presence of two subscribing witnesses.

JOHN F. KERR.
